DOUBLE POWER COMBUSTION MOTOR
WITH REDUCED FRICTION

Peter Scheschkewicz, Kazlu-Ruda, Lithuania

Application February 26, 1931, Serial No. 518,453
In Lithuania February 27, 1930

1 Claim. (Cl. 123—63)

- This invention refers to a double power combustion motor with reduced friction. An object of the invention is to reduce to a minimum the friction losses of the motor and, by establishing two compression spaces on both sides of the cylinder, to obtain a double acting power impulse for each piston, so that a two cylinder motor may be used as a substitute for a four cylinder one.
- Another object is to reduce the space required for the motor and to diminish its weight, both requirements being very important for the application of the motor to automobiles, flying machines, etc.
- The motors used hitherto have the disadvantage that a twofold power can never be obtained with an equal diameter and, furthermore, that the side pressure of the pistons on the cylinder walls, called forth by the tangential pressure of the crank machinery driving gear, cannot be eliminated, and that it is not possible to provide a combustion chamber at the lower end of the cylinder, because the connecting rod is placed in the middle of the cylinder.
- Another object of the present invention is to eliminate all these drawbacks.
- The invention will be more fully understood from the following detailed description when taken in connection with the annexed drawings showing a preferred embodiment of the inventive idea.
- In the drawings:
- Figure 1 is a longitudinal section through the motor.
- Figure 2 is a cross section through one of the cylinders.
- Figure 3 is a cross section through a cylinder and a cross-head.
- Figure 4 is a vertical section through this cross-head.
- Figure 5 is a longitudinal section through a motor of a somewhat different construction.
- Figure 6 is a cross-section through the motor shown in Figure 5.
- Figure 7 is a diagram showing the position of some parts illustrated in Figs. 5 and 6.
- The modification shown in Figures 1 to 4 comprises a cylinder *a*. Wrist-pins *j* which carry the pistons *h* pass through openings or slots *b*. The machine is provided with an upper explosion chamber *f* and a lower explosion chamber *d*, as well as with valves *c* operated by valve stems *w*. The pistons *h* connected by wrist-pins *j* drive the pitmen *k* connected with crank portions *o* of the crank shaft *l* which is supported in bearings *m*, and comprises intermediate members *p*. The lower ends of the pitmen *k* are provided with bearings *n*.
- The cylinder *a* and the valve chamber are formed of one piece.
- The walls of the explosion chamber *d* form one piece with the crank shaft casing *e*. The walls of the upper explosion chamber *f* are made out of a separate piece. The cylinder *a*, the upper and lower explosion chambers *f* and *d*, and the crank casing *e* are connected with one another by bolts *g*. Since the piston operates on both sides, it is provided on both ends with piston rings *i*.
- Both pistons *h* have one common wrist-pin *j*, which passes through the openings *b* and which carries cross-heads *s* guided by members *r*.
- The crank shaft *l* is carried by four bearings *m*. Said crank shaft carries three pitman bearings *n*.
- The stud roller *t* lies in ball bearings *u* which are fastened by screws *v* to the cylinder body, as shown in Figs. 3 and 4. Two valves are actuated by each stud.
- An advantage obtained by this machine consists in the elimination of a one-sided friction between the piston and a cylinder wall during explosion; the remaining friction is only due to the slight pressure of the piston rings. The work of the machine is balanced to a considerable extent, because while explosion takes place on one side of the piston, the compression of the gases takes place on the other side. During the explosion on the other side of the piston, an exhaust of the gases takes place on the first-mentioned side. The actuating forces and the energy of the movable masses are balanced by this arrangement.
- A two-cylinder motor made in accordance with this invention requires only three connecting rods and three crank shaft bearings, while a corresponding four cylinder motor of the type used in prior art needs four connecting rods and five crank shaft bearings. The number of bearings is thus reduced by 23%. The friction surface of the rod bearings is diminished by 62%. Since the coefficient of friction of ball bearings forming a part of the cross-head *s* is 0.002, while the usual coefficient of friction of the piston is 0.02, the friction in the cylinders is reduced by 90% by employing such bearings.
- The modification shown in Figs. 5 and 6 comprises two pistons *h'* interconnected by a wrist-pin *j'* passing through the upper ends of two pitmen *k'*. A member *7* is rotatably mounted on the wrist-pin *j'* close to said end of each of the pitmen, and carries two pivots *8* and *9*

which pass through the ends of two levers 10 and 11, the opposite ends of which are rotatably mounted at 12 and 13 in the casing α' . The lower end of the rods k' are connected with crank portions σ' in a way similar to that shown in Figs. 1-4.

The position of the member 7 at the upper dead center is shown in full lines in Fig. 6, while its position at the lower dead center is shown by dotted lines. In the diagram illustrated in Fig. 7 the upper position is shown by the dotted line A B, while the lower position is shown by the broken line C D. An intermediate position is designated by the full line B C, and equal angles formed by the levers 10 and 11 and a horizontal line are designated by the letter ϕ . It will be noticed that in the upper position the pivot 8 lies in the same horizontal plane as the pivot 12, while in the lower position, the pivot 8 lies in the same horizontal plane as the pivot 11.

I claim:

In an internal combustion engine, in combination, a casing, a piston, a cylinder connected with said casing and adapted to surround a part of said piston, a wrist-pin carrying said piston and extending beyond said cylinder, a pitman situated outside of said cylinder and connected with said wrist-pin, a crank shaft extending parallel to said wrist-pin and connected with said pitman, an immovable bearing rigidly connected with said casing and situated outside of the cylinder walls, an oscillatable member connected with said wrist-pin adjacent to said pitman and situated outside of said cylinder, and an oscillatable lever having one end carried by said bearing, the opposite end of said lever being connected with said member, said member and said lever transmitting forces developed by the crank shaft and the pitman to said casing and thereby relieving the pressure upon said piston.
